MATERIAL UNLOADER

Raymond E. Exum, East Orange, N. J., assignor
to Allied Chemical & Dye Corporation, a cor-
poration of New York

Application March 19, 1946, Serial No. 655,579

9 Claims. (Cl. 262—13)

1

This invention relates to material unloaders, and more particularly to coal unloaders for hopper bottom railroad cars to effect discharge of the coal through the gate-controlled bottom openings of the cars.

In the transportation and delivery of coal in railroad hopper cars, for many causes, of which wet and freezing weather may be mentioned as examples, the coal becomes packed to such extent that it will not move toward and from the hopper discharge openings, resisting gravitational movement towards the outlets of the hoppers. Coal unloaders, heretofore suggested to take the place of workmen using crow-bars and pneumatic drills on the top of the coal until the coal loosens and slides, with consequent danger to the workmen, have been of complicated and cumbersome design, in some cases involving pneumatic hammers and requiring several passes of the mechanism back and forth along the length of the car, to effect reasonably complete discharge of the coal from the full width of the car.

Among the objects of the present invention is to provide a coal unloader, simple in design and construction, and, therefore, of low initial cost, requiring low maintenance costs, and highly efficient in operation, particularly in that it effects substantially complete discharge of coal, usually requiring a minimum number of passes of the unloader along the length of the car so to do.

Other objects and advantages of this invention will be apparent from the following detailed description thereof.

In the accompanying drawings forming a part of this specification and showing, for purposes of exemplification, a preferred embodiment of this invention, without limiting the claimed invention to such illustrative instance:

Figure 1 is a plan view of a coal unloader embodying this invention;

Figure 2 is a side elevational view of the coal unloader of Figure 1, the blade member being shown in elevated position;

Figure 3 is an end elevational view of the coal unloader of Figures 1 and 2, the telescopic supports for the blade member which is shown in its lowered position being fragmentarily shown to enable the showing of the remaining parts of this figure on a larger scale than would otherwise be possible.

Figure 4 is a sectional view through a telescopic support for the blade member, this figure being on an enlarged scale as compared with the other figures of the drawing and having the blade mem-

2

ber and two of the telescopic sections fragmentarily shown to enable the showing of the remaining portions on a larger scale than would otherwise be possible; and

5 Figure 5 is an end elevational view, somewhat diagrammatic in character, showing the position of the unloader relative to a railway car.

Referring to Figure 5 of the drawing, 10 indicates conventional railroad tracks on which 10 travel a railway car 11 of the hopper-bottom or other type commonly used for transportation of coal. A suitable structural framework bridging the tracks 10, made of spaced channel bars 12, suitably braced and desirably provided with a 15 roof 13, is provided at the coal unloading station. Rails 16 on which the carriage 17 of the unloader travels are mounted on the sides of this structural framework, near the top thereof. A platform 18 having a handrail 19 is secured to one side of 20 this structural framework from which platform an operator may have ready access to the cab 20 depending from the carriage 17.

As disclosed in Figure 1, the carriage 17 consists of longitudinally extending channel bars 21, 22 25 and transverse channel bars 23, 24 suitably fastened at their ends and braced by braces 25. A pair of longitudinally extending axles or shafts 26, 27 are suitably journalled in this carriage and have, keyed thereon for rotation therewith, 30 wheels 28 adapted to travel on tracks 16. To maintain the wheels in firm engagement with the tracks 16, the carriage 17 is provided with depending extensions 29 (Figure 2) at each of the four corners thereof, and each having mounted thereon a roller or wheel 30 engaging the under- 35 side of the track 16.

Each of the axles 26 and 27 are arranged to be 40 rotated to effect rotation of the wheels 28 so that the carriage may be moved longitudinally on the tracks 16 relative to the car positioned therebelow for unloading purposes. Thus the axle 26 may be rotated by motor 31 (Figure 1) suitably mounted on the carriage and driving, through a gear reducer 32 of conventional design, gearing 33, which effects rotation of shaft 26. In like manner a motor 34 drives through gear reducer 35, gearing 36, which effects rotation of shaft 27.

45 A blade 37 of a width slightly less than that of the width of the railroad car 11, so that it can enter the car and extend across the full width thereof, except for small clearance between the ends of the blade and the side walls of the car, is 50 mounted on the carriage 17 for movement in a downward direction, into the body of coal in the car therebeneath, and in an upward direction to 55

the position shown in Figure 2. This blade is preferably a heavy steel plate provided with a cutting edge at its lowermost portion so that it readily enters the body of coal. It is carried by two sets 38, 39 of telescoping sections, one set being disposed near each end of the blade and the lowermost section of each set being fastened to the blade as indicated by the reference characters 40, 41. Vertically extending sleeves 42, 43 are rigidly fastened to the carriage 17 by plates 43' to guide movement of the telescopic sections so that the blade moves in a vertical plane.

Since both sets of telescoping sections are the same, only one will be described in detail; the parts of both sets of telescoping sections have been given like reference characters. With reference to Figure 4, each set of telescoping sections comprises a top cylindrical section 44 in sliding engagement with the sleeve 42 or 43; as the case may be, having a stop plate 45 welded or otherwise secured to its top and a cylindrical bearing sleeve 46 in the interior of the lower portion thereof. A cylindrical spring 47 is disposed about the top portion of section 44 between stop plate 45 and flange 48 on the sleeve 43 to cushion movement of section 44 in a downward direction. A second cylindrical telescoping section 49 is mounted for sliding movement in frictional contact with the bearing sleeve 46. This section 49 has a collar 50 suitably fastened to its top, which collar is in frictional contact with the inner wall of the first-mentioned section 44. The collar 50 and the cooperating bearing sleeve 46 prevent separation of the telescoping sections 44 and 49; further, when collar 50 engages the top of bearing sleeve 46, further downward movement of section 49 relative to section 44 is prevented. A cylindrical spring 51 is disposed in the space just above the top of sleeve 46 to cushion downward movement of section 49 toward the end of its travel in a downward direction.

A third telescoping section 52 is mounted for sliding movement in frictional contact with a bearing sleeve 53 in the interior of the lower portion of section 49. Each of the bearing sleeves 46, 53 are maintained in position at the lower portions of the interiors of sections 44 and 49, respectively, by collars 54, 55 having flanges 56, 57 at the lower portions thereof. The top portion of telescoping section 52 has a collar 58 suitably fastened thereto for sliding engagement with the interior wall of the telescoping section 49; which collar cooperates with sleeve 53 to prevent separation of sections 49 and 52. The lower portion of telescoping section 52 is fastened to the blade 37. A cylindrical coil spring 59 is disposed just above the top of the sleeve 53 in the space between the outer wall of the cylindrical section 52 and the inner wall of section 49, and serves to cushion downward movement of section 52 towards the end of its travel in a downward direction.

The above described construction of the telescopic sectional support for the blade 37 provides a compact and relatively inexpensive mounting for this blade which efficiently guides the blade in its downward movement and permits the disposition of the blade, when the machine is in position over the coal car, at a relatively great height above the coal so that upon release of the blade, as hereinafter more fully described, it drops under its own weight and functions to loosen the packed coal and become deeply embedded in the coal. Upon actuation of the carriage, as hereinafter more fully described, to move the blade in a lon-

gitudinal direction relative to the car, the blade acts as a "bulldozer" to force the coal in front of the blade towards the discharge opening. Furthermore, the mounting permits the blade to settle through the charge of coal and upon actuation of the carriage, to follow the contour of the bottom or floor of the car; hence substantially complete removal of the coal from the car is effected. While the construction shown in the drawings involves the use of two sets of telescopic sections for carrying the blade 37, one set being disposed near each end of the blade and each set consisting of three sections, it will be understood a greater number of sets may be used, and the number of sections in each set may involve more than three sections, if desired.

In the construction shown in the drawings, the stop plate 45, when the blade 37 is in lowered position, is disposed at a level approximately equal to that of the top of the carriage 17. When the blade is elevated to its upper position, the top telescopic sections 44 of both sets of telescopic sections move through the sleeves 42, 43 and are disposed with the stop plates 45 above the carriage 17, as shown in Figure 2.

To effect the raising of the blade 37 from its lowermost position, a cable or chain 60 (Figure 3) has one end fastened to the top of the blade 37 as at 61, and the other end secured to the drum 62 of a motorized hoist disposed on carriage 17. This motorized hoist, as shown in Figure 1, preferably comprises the drum 62 rotatably mounted in bearing supports 63' and arranged to be rotated by a motor 63 which drives a gear train 65, effecting rotation of the drum 62. A clutch 64 is interposed between the motor 63 and the gear train 65 so that the motor drive may be disconnected from the drum 62 to permit the drum to rotate under the action of the weight of the blade 37. When it is desired to elevate the blade, the clutch 64 is actuated to place the motor 63 in driving engagement with the drum 62.

Preferably, the bottom of the blade 37 is provided with a manifold pipe 66 having a plurality of openings therein, spaced along the length thereof and connected through a flexible hose 67 with an air tank supplied with compressed air, which air tank and the compressor associated therewith may desirably be disposed on the carriage 10 or may be located at some other suitable point. Air under pressure is supplied to the manifold 66 for effecting removal of the dust and fine coal from the bottom of the car, as hereinafter more fully described.

The control mechanism for effecting operation of the motors 31, 34 and 63 is disposed in cab 20 so that the operator therein can effect energization and deenergization of these motors by operating the usual controls employed for this purpose; operation of the clutch 64 is also controlled by conventional mechanism disposed in the cab 20.

In operation, the carriage 17 is moved in position over the car to be unloaded; with the blade member in the elevated position shown in Figure 2. When it is desired to effect discharge of the coal from the car, clutch 64 associated with motor 63 is actuated to disconnect the drive between motor 63 and the hoist, permitting the blade 37 to drop under its own weight into the coal therebeneath. The blade embeds itself deeply into the coal; the operator in the cab 20 then actuates the motors 31, 34 to cause the carriage to move longitudinally along the track 16, thereby forcing the coal toward the opening in

the bottom of the car and effecting its discharge therethrough. Due to the use of the telescopic sections supporting the blade 37, the blade moves in a vertical plane. By properly positioning the carriage 17 relative to the car 11 therebeneath, the blade may be caused to enter the car at one end thereof, so that by moving the carriage 17 away from this end of the car, substantially complete discharge of the coal in the car is effected. Furthermore, as above indicated, the blade has a tendency to settle completely through the charge of coal to the bottom of the car and, by actuation of the carriage, to follow the contour of the bottom of the car, thereby effecting substantially complete removal of the coal from the car. After the coal has been removed from the car, the carriage may be moved to its starting position by operating the motors 31, 34 in a reverse direction. Air under pressure is then admitted to the manifold 66, the blade being in its lower position and the motors 31, 34 again energized to cause the carriage 17 to travel in a direction longitudinally of the car so that the dust and fines are blown from the bottom of the car into and through the discharge opening.

It will be noted the unloader of this invention is simple in design and construction, involving, as it does, (a) telescopic sections supporting the blade 37, which telescopic sections are guided in sleeves 42, 43 fastened to the carriage, and (b) a motor drive for elevating the blade only, the blade dropping by gravity through the coal in the car. In practice, it has been found that with the construction disclosed, sufficient momentum is imparted to the blade before it strikes the coal charge to embed itself deeply into the coal charge, even when coal subjected to freezing temperatures is being unloaded, and that substantially complete discharge of the coal from the car is accomplished usually by a minimum number of passes of the machine along the length of the car. The machine in operation has been found to involve unusually low maintenance cost and to be highly efficient.

While the invention has been described in connection with the unloading of coal from railway cars, it is to be understood it may be used for unloading other material from other vehicles and containers, and hence this invention is not restricted to the present disclosure otherwise than as defined by the appended claims.

What is claimed is:

1. A material unloader comprising, in combination, a carriage, spaced guide bearings on said carriage, a blade, means disposed on said carriage for carrying said blade, said means comprising a plurality of sets of telescopic sections, each set being individual to a guide bearing, the lowermost section of each set being secured to the blade and the uppermost section of each set passing through one of said guide bearings, and means for actuating said blade to effect unloading of said material.

2. A material unloader comprising, in combination, a carriage, spaced guide bearings on said carriage, a blade, means disposed on said carriage for carrying said blade, said means comprising a plurality of sets of telescopic sections, each set being individual to a guide bearing, the lowermost section of each set being secured to the blade and the uppermost section of each set passing through one of said guide bearings, and means for raising and lowering said blade, said last mentioned means being constructed and ar-

ranged to permit the blade to drop into the material to be unloaded under its own weight.

3. An unloader for material in a container comprising, in combination, a carriage mounted to travel above said container, spaced bearing supports on said carriage, a blade, a plurality of sets of telescopic sections, each set being individual to a bearing support, the outermost section of each set passing through one of said bearing supports and the innermost section of each set being fastened to said blade, means for moving said carriage, and means for elevating said blade to cause said telescopic sections to be moved into nesting position with the outermost telescopic sections passing through said bearing supports, said last mentioned means being constructed and arranged to permit said blade to move under its own weight in a downward direction.

4. A coal unloader for a railroad car comprising, in combination, a carriage arranged to travel above the car, a plurality of bearing supports extending in a downward direction from said carriage, a plurality of sets of telescopic sections, each set being individual to a bearing support, the outermost section of each set passing through one of said bearing supports, a blade of a width slightly less than the width of the car, said blade being carried by the lowermost telescopic sections of said sets, and means for actuating said blade to effect its movement into and withdrawal from the car.

5. A coal unloader for a railroad car comprising, in combination, a carriage arranged to travel above the car, a plurality of bearing supports extending in a downward direction from said carriage, a plurality of sets of telescopic sections, each set being individual to a bearing support, the outermost section of each set passing through one of said bearing supports, a blade of a width slightly less than the width of the car, said blade being carried by the lowermost telescopic sections of said sets, and means for raising and lowering said blade, said last mentioned means being constructed and arranged to permit the blade to drop under its own weight.

6. A coal unloader for railroad cars comprising, in combination, a carriage mounted to travel on tracks disposed above the railroad car, a pair of cylindrical bearing supports extending in a downward direction from said carriage, a pair of cylindrical telescopic sections, the outermost section of each set passing through one of said bearing supports, a blade member of a width slightly less than the width of the car, said blade member being carried by the lowermost telescopic sections, means for moving said carriage on said tracks, a motor driven hoist, a cable connecting said hoist with the blade for elevating said blade, and a clutch in the motor hoist drive whereby the motor for said drive may be disconnected from the hoist to permit the blade to drop under its own weight.

7. A coal unloader as defined in claim 6, having a manifold main on the lower portion of said blade.

8. A material unloader for a container comprising, in combination, a carriage arranged to travel above the container, a plurality of bearing supports on said carriage, a blade, a collapsible and extensible mounting for said blade comprising a plurality of sets of telescopic sections, each set being individual to a bearing support, the outermost section of each set passing through one of said bearing supports and the lowermost 75 telescopic section of each set being fastened to

said blade, and means for actuating said blade to effect unloading of said material from said container.

9. A material unloader for a container comprising, in combination, a carriage arranged to travel above the container, a plurality of bearing supports on said carriage, a blade of a width slightly less than the width of the container, a collapsible and extensible mounting for said blade comprising a plurality of sets of telescopic sections, each set being individual to a bearing support, the outermost section of each set passing through one of said bearing supports, and the lowermost telescopic section of each set being fastened to said blade, and means for collapsing and extending said mounting to raise and lower said

5

blade, said last-mentioned means being constructed and arranged to permit the blade to drop into the material to be unloaded under its own weight.
